UNITED STATES PATENT OFFICE.

GEORGE E. EVANS, OF WACO, TEXAS.

COTTON-GIN FEEDER.

Application filed August 28, 1923. Serial No. 659,733.

To all whom it may concern:

Be it known that I, GEORGE E. EVANS, a citizen of the United States of America, residing at Waco, in the county of McLennan 5 and State of Texas, have invented certain new and useful Improvements in Cotton-Gin Feeders, of which the following is a specification.

This invention relates to new and useful 10 improvements in cotton gin feeders.

Those feeders now in common use employ a pair of pawls engaging a ratchet wheel, usually one pushing and one pulling, but occasionally both pawls are mounted to pull 15 or to push alternately. The result of such arrangements is that when one pawl is at the end of its stroke, the opposite pawl is at the starting point of its stroke. From this it will be seen that at this point, neither pawl 20 is acting upon the ratchet wheel. Further each pawl will increase its speed of travel to the center of its stroke and decrease its speed of travel to the end of its stroke. With such operations the cotton is not continuously fed in equal quantities. 25

The object of my invention is to provide means for continuously feeding the cotton in equal quantities and whereby the feed rollers are caused to steadily revolve and effect a 30 more uniform distribution of the cotton fed to the gin.

A further object of the invention is to provide a plurality of pawls working on the ratchet wheel continuously, whereby the latter is constantly rotated at a desired speed. 35

A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a side elevation of a feeding mechanism constructed in my invention,

Fig. 2 is a rear elevation of the same,

Fig. 3 is an enlarged sectional view on the line 3—3 of Fig. 1,

Fig. 4 is a side elevation of a modified form,

Fig. 5 is a front elevation of the same, and

Fig. 6 is a plan view.

In the drawings the numeral 10 designates the usual ratchet wheel which is fastened on the end of the shaft 11 of a gin feeder roll. The picker roll has a shaft 12 on which is

mounted a pinion 13 driving a gear 14 mounted on the end of the feeder frame. A bell crank lever 15 is pivoted on a stud bracket 16 and has its lower end slotted to 60 receive an adjustable pivot connection 17 mounted on the end of a pitman 18. The pitman has its opposite end pivoted on a stud 19 on one of the spokes of the gear 14. When the gear is revolved, the pitman 65 swings the lever and the throw of the latter is lessened or increased by adjusting the pivot connection, 17.

On the upper leg of the lever 15 is slidably mounted a pivot block 20 held in position 70 by a set screw 21. Pawl arms 22 have their lower ends overlapping and pivoted in the upper end of the block 20. By adjusting the block the stroke of the arms can be lengthened or shortened. These arms diverge, 75 extending upwardly on each side of the face of the ratchet wheel 10. The arms have oppositely directed pawls 23 pivoted on their upper ends, which are supported by links 24 pivoted on the end of the shaft 11. When the gear 14 is revolved, the arms are moved up and down by the lever 15, one pawl feeding while the other travels over the teeth of the ratchet 10, for a fresh bite. 80

The parts so far described are found on a widely used feeder and are open to all the objections herein set forth. It is obvious that the pawls will feed faster at the center than at the ends of their strokes and there will be a pause in the feed at the ends of 90 the strokes.

In overcoming these objections I mount a lever 25 intermediate its ends on a fulcrum stud 26. On one end of the lever a pivot block 27 is slidably mounted and held by a set screw 28; while the opposite end of the lever is slotted for receiving an adjustable pivot connection 29 attached to the upper end of a pitman 30. The lower end of the pitman 30 is pivoted on the stud 19. Diverging pawl arms 31 overhanging the ratchet wheel 10 have their upper ends pivoted in the block 27. One of the arms has a pushing pawl 32 on its lower end; while the other arm has a pulling pawl 33 on the lower end 100 of its arm. These pawls operate alternately.

It is important that the pitmen 18 and 30 be at substantially right angles to each other, so that when one pair of pawls is at the end of their stroke, the other pair will 110 be at the center of their stroke at which they will be at their highest speed of travel and

will decrease in speed toward the end of their stroke. While the second pair of pawls is reducing in speed from the center to the end of their stroke, the first pair of pawls will be increasing in speed from the beginning of their stroke to the center thereof. By this arrangement a desired speed and a continuous feed will be obtained. Any substantial variation from the relative 10 position of the pitmen will diminish the effectiveness of the device. There will be no point when the ratchet wheel is not being acted upon by the pawls.

In Figs. 4 to 6 I have shown a modified 15 form in which a crank 34 takes the place of the lever 15. On the crank are pivoted the lower ends of pitmen 35 receiving the ratchet wheel 10' between their upper ends which are pivoted to the lower ends of supporting links 36. Oppositely directed pawls 37 are pivoted on the upper ends of the pitmen and alternately actuate the ratchet wheel. A gear 14' is driven in mesh with a pinion 13' mounted on a roller shaft 25 12'. The ratchet wheel is mounted on a roller shaft 11'.

The crank 34 is attached to the shaft of the gear 14' and has a crank arm 38 offset therefrom at substantially forty-five degrees. A double crank 39 is mounted in a bracket 40 above the ratchet wheel. The crank members are offset at an angle of about forty-five degrees. A pitman 42 extends from the crank arm 38 to the offset 30 35 crank member 41. The offset crank member 43 has pivoted thereto the upper ends of a pair of pawl arms 44 straddling the upper portion of the ratchet wheel. One of the arms has a pushing pawl 45 and the other arm is provided with a pulling pawl 46. A fourth pitman 47 extends from the crank 34 to the central member of the crank 39.

It will be seen that the driving point of the crank arm 38 is at substantially right 45 angles to the driving point of the pitman 47 and with the pitman 42 operating the pawl arms 44, substantially at right angles to the pitmen 35, whereby similar results are had to those pointed out in connection with the 50 form shown in Figs. 1 and 3. The modified form is not as desirable as the first form, because the adjustments for controlling the actuation of the ratchet wheel are not included in the modified form. It 55 is customary with the modified form to employ suitable means, (not shown) working between the pawls and the ratchet teeth to hold the pawls out of the teeth during a portion of the stroke.

While I have shown the device in connection with two forms of feeders, it may be used in connection with other forms. The stud 19 and gear 14 and the crank 34 constitute driving members.

Various changes in the shape, size and location of the different elements as well as modifications may be made within the scope of the appended claims.

What I claim, is:

1. In a gin feeder, a ratchet wheel, a driving member, a pair of pawls engaging opposite sides of the lower portion of the ratchet wheel, a pitman connected with the driving member to actuate said pawls, in connection with a second pair of pawls engaging opposite sides of the upper portion of the ratchet wheel, a lever to which said second pair of pawls are connected by a common pivot at one side of its axis for movement toward and from the axis of the wheel, and a pitman connecting the last named lever with the driving member at substantially a right angle to the first named pitman.

2. In a gin feeder, a ratchet wheel, a driving member, a pair of pawls engaging opposite sides of the lower portion of the ratchet wheel, a pitman connected with the driving member to actuate said pawls, in connection with a pair of push and pull pawls engaging opposite sides of the upper portion of the ratchet wheel, a lever, a block thereon having a common pivot for the push and pull pawls, said block being disposed of movement substantially radially of the axis of the wheel, and a pitman connecting said lever with the driving member at an angle to the first named pitman.

3. In a gin feeder, a ratchet wheel, a driving member, a pair of pawls engaging opposite sides of the lower portion of the ratchet wheel, a bell crank lever to which said pawls are pivoted, a pitman connected with the driving member and pivoted to the lever, in combination with a second pair of pawls comprising push and pull members and engaging opposite sides of the upper portion of the ratchet wheel, a lever to which said second pair of pawls are adjustably pivoted at one side of the axis thereof and a pitman pivoted connecting the last named lever with the last named pitman having its pivot in common with the first named pitman on the driving member and extending at substantially right angles to the first named pitman.

In testimony whereof I affix my signature.

GEORGE E. EVANS.
